UNITED STATES PATENT OFFICE.

ABRAHAM MAX HOLTZMAN, OF BROOKLYN, NEW YORK.

SELF-PROPELLED SADIRON.

1,331,107.

Specification of Letters Patent. Patented Feb. 17, 1920.

Application filed November 22, 1918. Serial No. 263,682.

To all whom it may concern:

Be it known that I, ABRAHAM MAX HOLTZMAN, a citizen of the United States, and resident of the borough of Brooklyn, county of 5 Kings, city and State of New York, have invented certain new and useful Improvements in Self-Propelled Sadirons, of which the following is a specification.

The device, the subject of this invention 10 is a sad iron intended for all of the uses of the common type of sad iron for pressing, straightening and finishing. I have however, discovered that in certain classes of work, particularly in the pressing of very 15 heavy outer garments the ordinary sad iron does not meet the requirements because of the fact that the weight of an iron is limited by the strength of the operator, and that because of the difficulty in moving the 20 iron about many operators must employ light irons to which must be added the strength of the operator in depressing the iron upon the goods over which the iron is to be passed.

25 One of the principal objects of my invention then is to provide an iron which can be made of very great weight, one which will however, operate as readily or even more readily than the ordinary hand propelled iron.

30 I provide means for moving the iron in any direction, means for heating the iron continuously while under use and means for removing the iron from the work without the necessity of manually lifting the iron in 35 the customary manner. All of these features and the construction of my device will be set forth as the specification progresses.

The following is what I consider a good 40 means for carrying out my invention and the accompanying drawings should be referred to for a complete understanding of the specification which follows:

In the drawings:—

45 Figure 1 shows in elevation an ironing table upon which are arranged my improved iron and the support or retriever therefor.

Fig. 2 is a sectional view of the iron.

50 Fig. 3 shows in elevation the current controlling device.

Fig. 4 shows a detachable presser foot.

Similar reference numerals indicate like parts in all the figures where they appear.

At 1 I show a table or stand upon which my iron may operate. This table may be 55 of any ordinary shape or size and therefore requires no further description.

Secured at one end of the table is a cylinder 2 having an upward projection 3 and through the cylinder I extend a shaft 4 provided with a collar 5 and a spring 6 tends to depress the shaft 4.

Pivoted to the upper end of the shaft 4 is a lever or arm 7, the extreme outward end of which is slightly upturned as indicated at 8. This lever 7 bears upon a projection 3 of the member 2 and when the spring 6 depresses the collar 5 the outer end 8 of the lever 7 is elevated.

The device just described is the support 70 or retriever for my iron and when engaged with the iron this retriever will elevate the iron from the table and support it elevated.

The iron proper is provided with a pressing cylinder 9 which may be of any diameter, weight and size. This cylinder is electrically heated as will be later described and the cylinder is supported upon a shaft 10 which shaft is free to rotate in suitable bearings in the frame 11 of the iron. Upon the 80 shaft 10 I arrange a sprocket 12.

A motor 13 supported in the frame 9 carries a sprocket 14 and a chain 15 from the sprocket 14 on the motor shaft to the sprocket 12 on the shaft 10 rotates the shaft 85 and the cylindrical member 9.

Formed integral with the frame 11 is an extension 16 at the lower end of which is a presser foot 17 and this presser 17 is also electrically heated as will be more fully here- 90 inafter described.

Connected with the top of the frame 11 are brackets 18 and 19 between which is a handle 20; the handle 20 may be partially rotatable and a shaft 21 extending therefrom engages with the lever 22 of the controlling switch shown in Fig. 3 and an eye or lug 24 also secured to the frame is adapted to receive the end 8 of the lever 7 and should be engaged therewith when the iron 100 is not in use.

I provide a socket 25 to which a plurality

of current carrying wires may be attached and I may also provide a small fan 26 inclosed by a suitable guard. This fan is connected upon the motor shaft and performs the ordinary functions of a fan in cooling the atmosphere adjacent to the iron, the use of the fan may however, be dispensed with.

Now referring to Fig. 2 I will describe the construction of certain of the parts.

10 The cylinder 9 may be of iron or steel, one or both of the ends may be removable as desired, within the cylinder I arrange a plurality of heating coils 28, 29 and I connect these coils one end of each coil extending through the end of the cylinder to a button 30 or 31 and the other end extending through the opposite end of the cylinder to the buttons 32 and 33 and it will be understood that I may provide any number of 15 coils within the cylinder and corresponding buttons upon the ends of the cylinder but insulated therefrom.

The end members of the cylinder should be recessed and a shaft 10 passing through 25 the cylinder should be secured thereto by means of nuts 34 and 35 so that the cylinder will rotate with the rotation of the shaft 10.

Disks 36 and 37 are arranged one at each 30 end of the cylinder and bear upon the contacts 30—33. These disks 36 are insulated from the shaft and from all surrounding mechanism by flanged sleeves 38 and 39 and a spring washer 40 or 41 presses the disks 36 or 37 inward upon adjacent contacts and an 35 insulating pin 42 or 43 passing through the disks 36 or 37 and the springs 40 and 41 prevents the rotation of the disks and springs.

40 A wire from the line lead or source is connected to the disk 36 and another wire from the source of current supply is connected to the disk 37 and when so connected and current is allowed to flow through the wires the coils within the cylinder will become heated, heating the cylinder to a 45 desirable degree.

I also provide heating coils 43 in the foot or drag member 17 but as these coils are stationary with the frame of the iron ordinary permanent connections may be employed to pass current through these coils.

The switch shown in Fig. 3 is in diagram 50 and serves to show the connections of the wires and line leads to the motor as I prefer that the motor should be reversed or should travel in either direction as shall be desired or required. No switch need be supplied for the heater coils as the current passing through these coils may be controlled by a 55 switch exterior to the iron.

Let us now consider the operation of this device.

In the first place I desire that the frame 11, the cylinder 9, and the foot piece or

drag 17 should be heavy. In my experiments I have determined that the total weight of this iron may be greater than any weight found possible with a hand-propelled iron, although the weight need not be considered an important feature in the construction of the iron, provided that it be sufficient to meet requirements.

While the iron is upon the supporting lever 7, the current may be caused to pass into and through the heater coils and when 75 the cylinder 9 and foot piece or drag 17 are sufficiently heated the iron may be disengaged from the lever 7, the handle 20 of the iron turned slightly so that the switch lever 22 will contact with the first point P of the 80 controlling switch shown in Fig. 3. The motor will start to revolve slowly, the cylinder 9 will also revolve and the iron will move forward or in the direction of the arrow in Fig. 1. The speed may be increased 85 by a thorough turning of the handle 20, but I desire a comparatively slow motor so that the rate of travel of the cylinder will not be so great as to move the iron materially faster than an ordinary pressing iron is moved. 90 When the end of the seam or garment is reached the iron may be turned around or if desired its direction of motion may be reversed. A reversed or backward movement 95 of the iron may be accomplished by turning the handle 20 in the opposite direction, this will cause the lever 22 to pass through the center of its travel and over or across the other contacts C of the switch. Here the speed of movement may be increased at will 100 and I prefer that the rate of travel in either direction shall be approximately the same. When the handle is brought back to the position shown in Fig. 3 the switch lever 22 will rest on the dead contact, the motor 105 will stop and the iron come to rest.

If required an ordinary jack shaft may be employed for reducing the speed of travel but as the use of a jack shaft is well understood I need not show the arrangement of 110 such a shaft and I prefer that my device should be direct connected.

Modifications may be made within the scope of the appended claims without departing from the principle or sacrificing 115 the advantages of this invention.

The presser foot may be made detachable if such is desired.

Having carefully and fully described my invention what I claim and desire to secure 120 by Letters Patent is:—

1. A self-propelled sad iron having a cylinder and means for rotating it and a non-rotatable drag and means for heating said cylinder and said drag.

2. A self-propelled sad iron having a frame, a cylinder rotatably mounted in said frame, means carried by said frame for ro-

tating said cylinder and a non-rotatable drag upon said frame and means for heating said cylinder and said drag.

3. A self-propelled sad iron having a rotatable cylinder and a non-rotatable drag and means for heating said cylinder and said drag and a handle for directing said iron.

4. A self-propelled sad iron having a cylinder and means for heating it, means for 10 rotating said cylinder, means for controlling the speed of rotation of said cylinder and a non-rotatable drag.

5. A self-propelled sad iron having a cylinder, means for heating said cylinder, 15 means for rotating said cylinder, means for

controlling the rotation of said cylinder and for changing the direction of rotation and a non-rotatable drag.

6. A self-propelled sad iron having a frame and a shaft extending therethrough, 20 a cylinder upon said shaft, heating coils within said cylinder, means supported by said frame for electrically connecting said coils with a source of current supply, a motor within said frame and connected with 25 said shaft for rotating said cylinder and a non-rotatable drag on the frame.

Signed N. Y. city, Oct. 4, 1918.

ABRAHAM MAX HOLTZMAN.
